CLAIM

The ornamental design for a triangular tri-pack container, as shown and described.

DESCRIPTION

FIG. 1 is a front perspective view thereof, showing a triangular tri-pack container of my new design;

FIG. 2 is a front elevational view thereof;

FIG. 3 is a side elevational view thereof;

FIG. 4 is a an elevational view of that side of the container opposite the side shown in FIG. 3;

FIG. 5 is a top view thereof;

FIG. 6 is a bottom view thereof; and,

FIG. 7 is a front perspective view of the tri-pack container of FIG. 1, with the surmounting closure cap lifted to expose the three capped, triangular containers concealed thereby.
